(57) **CLAIM**

The ornamental design for a film sheet for use in antiballistic articles, as shown and described.

DESCRIPTION

FIG. 1 is a top plan view of a film sheet for use in antiballistic articles according to our new design; and, FIG. 2 is a bottom plan view, thereof.

The broken lines surrounding the design indicate the boundaries of the claim and form no part thereof. The design is flat and planar and the thickness of the film sheet for use in antiballistic articles forms no part of the claimed design.
